UNITED STATES PATENT OFFICE.

MORGAN PARKER, OF NEW YORK, N. Y.

SCISSORS.

Application filed August 20, 1921. Serial No. 493,935.

This invention relates to scissors having replaceable blades.

The constant resharpening and grinding of scissors is expensive and time-consuming and shortens the life of the instrument. Moreover, because of this grinding and the continual presentation of a new cutting edge the blade of the ordinary scissors is made of cutlery steel throughout, a construction which is not only expensive, but one which introduces manufacturing difficulties. The use of compound blades is old, but in such construction the blade is made of a heavy piece of steel permanently or semipermanently attached to a softer metal shank. The problem of drop-forging the shank is thereby simplified, but it still remains necessary to resharpen the blade, and to grind it with serrated cutting edge commonly found in scissors, particularly barbers' shears.

A light, cheap blade, readily attached to and detached from the shank, and so inexpensive that it might be replaced when dulled at less than the cost of resharpening, would solve the problem. Such a blade must, however, be held in tight contact with its shank to their extreme outer co-terminus, as otherwise any space between them would be likely to catch a hair or thread and cause trouble. The blade must also be designed for quick and easy positioning and removal and must nevertheless be securely locked in position during use. Moreover, as the blade must be inexpensive it should be ground straight, but for this reason must be flexible enough to conform to the curve of the shank.

It is accordingly the object of this invention to design a pair of scissors having such light, cheap, replaceable blades, readily attachable and detachable and firmly held upon their shanks when in use. The manner in which this is accomplished will be apparent from the following description and its accompanying drawings. Although two preferred embodiments of the invention have been shown and described it is obvious that the principles involved are not limited to these specific forms.

In these drawings Fig. 1 is an elevation of a pair of scissors equipped with removable blades in accordance with this invention and shown in wide open position. Fig. 2 is an enlarged section through the shank taken in line 2-2 of Fig. 1; Fig. 3 is a similar view taken upon line 3-3 of Fig. 1; Fig. 4 is a fragmentary longitudinal section taken on

line 4-4 of Fig. 1; Fig. 5 is an elevation of one of the shanks with the blade removed; Fig. 6 is a view similar to Fig. 1, but showing a modified form of blade; Figs. 7, 8 and 9 are enlarged sections taken on line 7-7, 8-8 and 9-9 respectively of Fig. 6.

The scissors shown in these views are of the type commonly employed by barbers, but it is, of course, obvious that the invention is applicable to scissors and shears of any type. These scissors shown in Fig. 1 are provided with the ordinary shanks 1 pivoted together about a king pin 2. The inner face of each shank is provided with a dovetail strip 3 slightly raised above the face of the shank and extending from the tip about two-thirds to three-fourths the distance to the pivot, as shown most clearly in Fig. 5. The blade 4 is provided with a corresponding dovetail groove 5 extending its entire length. The working face of the shank is provided near its inner end with an upstanding projection 6 having an inclined face tapering upwardly and to the rear, as shown in Fig. 4. The blade is provided with a corresponding aperture 7 which cooperates with the projection 6 to lock the blade against longitudinal movement. When a blade is to be positioned upon its shank the scissors are opened to the extended position shown in Fig. 1 and the blade slipped longitudinally along the shank, the dovetail strip 3 entering the groove 5 in the blade. When the rear end of the blade encounters the projection 6 it rides up over it, this flexing movement being permitted because at that point the dovetail strip 3 has been cut away. Upon further sliding movement the aperture 7 coincides with the projection 6 and the blade snaps into place.

In the form shown in Figs. 6, 7, 8 and 9 a narrower blade is used, which extends for only a part of the width of the shank face, whereas in the foregoing form the blade is coextensive with the working face of the shank. In this form the shank is the female member, being provided with a longitudinal dovetail groove 7, which corresponds with a dovetail strip 8 on the blade, as shown most clearly in Fig. 7. In this form a projection or pin 9 projecting upwardly from the groove 7 near its inner end acts as the locking member and cooperates with an aperture 10 in the blade to prevent longitudinal displacement. In order to permit this locking member to function, which necessitates a flexing of the blade to ride

over it, the undercut of the groove 7 is cut away near its inner end, as shown in Figs. 6 and 8. Thus, for the inner end of the blade the dovetail connection is inoperative, and it is possible for the blade to flex as it rides over the pin 9 into locking position. It would, of course, be possible in this case to remove the overhang from the dovetail portion 8 of the blade, just as in the form shown in the other figures it would be possible to remove the undercut from the blade, but as the blade is the cheaper part and must be made in quantity, all the machine work possible should be done on the permanent shank.

Both forms of blades described above are designed to be positively held in tight contact with their respective shanks from their extreme co-terminus to a point well back along the blade. This prevents any outward springing of the blade near its tip and the opening up of a space which might catch upon a hair or thread. Besides, the dovetailed connection between blade and shank extending to their co-terminus presents a broken line at the tip of the scissors, and hence precludes the possibility of a hair or thread slipping between blade and shank. That part of the blade not positively held in contact with the shank is held in position by the mutual opposition of the shanks during ordinary use, and it is only when a blade is to be positioned or removed that the scissors are opened so wide that this mutual opposition is not effective. The means locking the blade against longitudinal displacement are simple and effective, the operation being dependent upon the resiliency of the blade itself. This resiliency and flexibility also make it possible for the blade to conform to the transverse curve, so common in scissors. The blade can also adapt itself to a slight twist in the shank. It is a simple matter to position such a blade, and an equally simple matter to remove one when it has become dulled and the necessity for replacing it by a fresh one has arisen.

This invention has been illustrated as applied to scissors, and it is in this connection that it will undoubtedly find its greatest usefulness, but it is obvious that the same

principles involved might be applied to cutlery of other forms.

I claim:

1. In removable blade scissors, the combination of a shank and a removable flexible blade, dovetail connection between the two along their outer lengths holding the blade in positive contact with the shank, an up-standing projection near the inner end of the shank, a hole in the inner end of the blade designed to cooperate with the pin to lock the blade against longitudinal displacement, the dovetail connection between the shank and the blade being cut away near their inner ends to permit the blade to flex and ride over the pin to locking position.

2. In removable blade scissors, the combination of a shank and a removable flexible blade, sliding connection between the two along their outer lengths holding the blade in positive contact with the shank, an up-standing projection near the inner end of the shank, a hole in the inner end of the blade designed to cooperate with the pin to lock the blade against longitudinal displacement, the sliding connection between the shank and the blade being cut away near their inner ends to permit the blade to flex and ride over the pin to locking position.

3. In scissors having a removable blade, means for positively holding the blade in contact with its supporting shank throughout the outer length of the blade, contact at the inner end depending upon the normal opposition of the other shank, and cooperating lock members on the shank and the inner end of the blade, the mounting of the blade on the shank being such as to permit flexing of the inner end of the blade toward and away from the shank to engage and disengage the lock members.

4. In scissors having a removable blade, means for positively holding the blade in contact with its supporting shank throughout the outer length of the blade, contact at the inner end depending upon the normal opposition of the other shank, and automatically operable means locking the blade against longitudinal displacement.

In testimony whereof I affix my signature.
MORGAN PARKER.

CERTIFICATE OF CORRECTION.

Patent No. 1,620,226.

Granted March 8, 1927, to

MORGAN PARKER.

It is hereby certified that error appears in the printed specification of the above numbered patent requiring correction as follows: Page 1, line 90, for the word "is" read "it"; page 2, line 100, after the word "displacement" insert a comma and the words ", the inner end of the blade being flexible toward and away from the shank"; and that the said Letters Patent should be read with these corrections therein that the same may conform to the record of the case in the Patent Office.

Signed and sealed this 26th day of April, A. D. 1927.

Seal.

M. J. Moore,
Acting Commissioner of Patents.
